DESIGN FOR A BASE FOR POULTRY FOUNT AND FEEDER

Max T. Bentzen and Jacob F. Niggeler,
Minneapolis, Minn.

Application February 7, 1941, Serial No. 98,810

Term of patent 14 years

To all whom it may concern:

Be it known that we, Max T. Bentzen and Jacob F. Niggeler, citizens of the United States, residing at Minneapolis, in the county of Hennepin and State of Minnesota, have invented a new, original, and ornamental Design for a Base for Poultry Fount and Feeder, of which the following is a specification, reference being had to the accompanying drawing, forming part thereof.

Fig. 1 is a perspective view of a base for poultry fount and feeder, showing our new design.

Fig. 2 is a diametrical vertical section through the device shown in Fig. 1.

We claim:

The ornamental design for a base for poultry fount and feeder, as shown.

MAX THUR. BENTZEN.
JACOB F. NIGGELER.
